PICKER

Leon W. Campbell, Hendersonville, N. C.

Application August 26, 1943, Serial No. 500,064

9 Claims. (Cl. 139—159)

The present invention relates to loom pickers, and has as its object to increase the useful life and improve the operation of loop pickers of the type applied to the end of pickersticks to propel and check the shuttle in its flight across the loom.

To these ends, the invention comprises a picker made of leather, rubber, plastic, or other suitable material preferably of non-metallic yielding or elastic nature, having its working face enclosed in a resilient metal casing which serves both to prevent or delay the destructive spreading and distortion of the picker out of usable condition under the pounding of the shuttle point, and also to create a relative movement and consequently a frictional resistance between the surface of the picker body and the contacting surface of the metal casing, when the parts are spread by impact of the shuttle, which consumes and dissipates some of the energy of the blow delivered against the picker by the shuttle point in picking or checking the shuttle. Preferably, the metal casing is apertured to admit the shuttle point to contact with the picker body without the shuttle engaging the metal of the casing, while the casing is made continuous entirely around such aperture to bridge the cleft and increase the support of the picker body against harmful spreading, and to cause the co-engaging surfaces to move in opposite directions during spreading. Preferably also, the portion of the picker body within the casing is cleft purposely to increase the spreading to a limited and controlled degree upon impact of the shuttle point thereon, and the encased portion of the picker body is made partly cylindrical or otherwise rounded and the interior casing is given a conforming shape, to maintain the maximum possible area of frictional contact between the outside of this portion of the picker body and the inside surface of the casing during the controlled spreading occurring during impact.

An illustrative embodiment of the invention is shown in the accompanying drawing, in which:

Fig. 1 is a side elevation, and Fig. 2 a face elevation of the improved picker secured in place on the upper end of a pickerstick.

Fig. 3 is a plan view of the parts of Figs. 1 and 2.

Fig. 4 is a plan view of the metal casing.

The picker body 1 of rubber, leather, plastic, or other suitable material, is of conventional loop form and dimensions except as to the parts

5 at and adjacent the working face thereof. Thus, it has a loop 3 which surrounds and wedges tightly on the top end of the pickerstick 5, being retained thereon in usual manner by the screw 7.

The working end 9 of the picker is made of usual height or depth, but in accordance with the invention is given a partly circular outline as viewed in plan in Fig. 3, so that the portion 9 has the shape of a partial cylinder having its axis substantially perpendicular to the top surface of the picker. In addition to the usual pilot hole 11 to receive and guide the shuttle point, the face of the picker body is slotted from top to bottom as indicated at 13, the slot being centered on the vertical median plane through the picker and its stick and thus including the axis of pilot hole 11 and the axis of the cylindrical portion 9.

10 A casing 15 of spring steel or other durable and highly resilient metal of C-shape in horizontal section encloses substantially the entire frontal and lateral surfaces of the working portion 9 of the picker, being given a cylindrical shape interiorly to conform closely and compressively to the exterior of cylindrical portion 9, the sides of the casing being carried around portion 9 well beyond the axis of the cylinder to grip the narrower neck occurring where the portion 9 joins the loop portion of the picker. The casing is sprung onto the cylindrical portion 9 by compression of picker 9 and combined slight spreading of the casing 15, whereafter casing 15 grips portion 9 tightly enough to be 15 secure against being flung off in use. Inturned flanges 17 extending around the top and bottom ends of casing 15 parallel to and in contact with the top and bottom ends of cylindrical portion 9 of the picker body prevent vertical displacement of the casing.

20 The face of casing 15 presented toward the shuttle is formed with a circular hole 19 concentrically disposed with respect to pilot hole 11 in the picker body, this hole being large enough so that its sides will avoid contact with the shuttle as long as the picker stays in shape for continued use. In fact, since the hole 19 is actually circular in shape, it becomes elliptical and thus wider in a lateral direction as the portion 9 of the picker body spreads in use, increasing the lateral clearance as the shuttle point penetrates more deeply.

25 In use, the impact of the picker upon the shuttle point in picking, or of the shuttle point upon the picker in checking the flight of the shuttle, causes

the conical shuttle point to spread the two halves of cylindrical portion 9 apart sidewise within the casing 15. This expansion of portion 9 in effect increases the circumference thereof, and though the casing 15 expands to permit it, the casing cannot increase its circumferential length, with the result that a substantial degree of relative circumferential movement is produced between the cylindrical surface of portion 9 and the interior surface of the casing 15. This gives rise to a substantial degree of friction between the surfaces in contact, which friction increases in proportion to the strength of the blow struck by the shuttle point, as the harder the blow the greater the expansion of portion 9 and the greater the resistance to spreading exerted by casing 15 and the greater the relative travel of the two surfaces in contact with each other. To a lesser degree the blow of the shuttle point spreads cylindrical portion 9 vertically, thus increasing the pressure of such portion against the inturned flanges 17 at top and bottom of casing 15, and this also adds to the braking surface which creates the friction desired to dissipate the energy of the blow. The same relative movement of the surfaces of portion 9 and of casing 15 along each other occurs throughout these areas of contact as arises within the lateral and frontal parts of casing 15.

By this construction, the energy which otherwise goes into tearing and spreading the ordinary picker apart until it is worn out and useless is largely dissipated harmlessly as heat, and the picker is held in shape and continues to remain serviceable for a greatly prolonged period.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but

What I do claim is:

1. A loom picker comprising an inner body and a resilient casing surrounding such body, such parts to be moved relatively to each other by the impact of the shuttle and by such movement creating friction between these parts dissipating a portion of the energy of impact.

2. A loom picker comprising a one-piece body having an integral loop gripping the pickerstick of the loom and a resilient casing fitting around the body, both the body and the casing being arranged to expand under the impact of the shuttle.

3. A loom picker comprising a body and a casing surrounding and engaging such body, both arranged to expand under the impact of the shuttle to produce relative sliding movement of the surfaces thereof in mutual contact.

4. A loom picker comprising in combination a body having a pickerstick loop and a part-cylindrical shuttle-engaging portion disposed transversely to the shuttle axis and a casing having an internal shape conforming to the surface of such portion and compressively fitting such surface.

10 5. A loom picker having in combination a body having a part-cylindrical shuttle-engaging portion disposed transversely to the shuttle axis, and a casing of C-shape in section fitting about such portion.

15 6. A loom picker having in combination a body having a part-cylindrical shuttle-engaging portion that is cleft in the plane of its axis, and a casing fitting closely and conformably about the cylindrical surface of such portion and bridging the cleft.

20 7. A loom picker having in combination a loop to fit upon the pickerstick and an integral portion engaging the shuttle, and a casing fitting around the latter portion, the surface of such portion moving along the coengaging inner surface of the casing in a direction away from the shuttle and the inner surface of the casing moving 25 in the opposite direction with respect to the coengaging surface of the said portion of the picker by reason of the expansion of said portion under impact of the shuttle against the picker.

30 8. A loom picker comprising in combination a body having a shuttle-engaging face having a slot entered by the shuttle-point, and a resilient one-piece casing extending across the face and bridging the slot therein and enclosing the lateral portions of the picker adjacent its face and expanding 35 and moving along and in contact with the said lateral portions when the body expands under impact of the shuttle.

40 9. A loom picker having in combination a loop to fit upon the pickerstick and a part-cylindrical shuttle-engaging portion that is cleft lengthwise through the point of impact of the shuttle thereon, and a resilient metallic casing bridging the cleft and clasping the cylindrical surface of the said portion and having portions overlying the top and bottom surfaces of such portion, the casing having an aperture admitting the shuttle-point to contact with the shuttle-engaging portion.
